R. O. DUNNING.

RECEPTACLE

FILED MAR. 5, 1921

By *Watson E. Coleman*
Clerk

UNITED STATES PATENT OFFICE.

ROBERT O. DUNNING, OF LEVANT, MAINE.

RECEPTACLE.

Application filed March 5, 1921. Serial No. 449,630.

To all whom it may concern:

Be it known that I, ROBERT O. DUNNING, a citizen of the United States, residing at Levant, in the county of Penobscot and 5 State of Maine, have invented certain new and useful Improvements in Receptacles, of which the following is a specification, reference being had to the accompanying drawings.

10 This invention relates to receptacles, and particularly to receptacles on the order of match boxes.

15 The general object of my invention is to provide a receptacle of this character adapted to be carried in a pocket, which will deliver one article, as for instance a match or a cigarette, at a time and which may be so modified as to deliver, say a match and a cigarette at the same time if desired.

20 A further object is to provide a device of this character embodying a body having a central storage compartment and a series of concentrically disposed delivery compartments, and provide a cover or cap for one 25 end of the device closing the inlet ends of the storage and delivery compartments; and a rotatably mounted cap upon the other end of the body which, as it is rotated step by step, will permit the discharge of one of 30 the articles from a delivery compartment.

35 And a further object is to provide means whereby this last named cap may be rotated in one direction step by step but will be prevented from rotation in the opposite direction.

40 Still another object is to provide the first named cap which closes the inlet end of the several compartments with means whereby it may be drawn down tightly upon the body and with means whereby it may seal this end of the body against moisture.

45 Other objects will appear in the course of the following description.

My invention is illustrated in the accompanying drawings, wherein:—

Figure 1 is an elevation of a match box constructed in accordance with my invention;

50 Figure 2 is a vertical section on the line 2—2 of Figure 1;

Figure 3 is an under side plan view of the match box;

Figure 4 is a section on the line 4—4 of Figure 2;

Figure 5 is a vertical sectional view of a 55 combined match and cigarette box;

Figure 6 is a top plan view thereof with the top cap removed;

Referring to these drawings, 10 designates a body which may be made of wood, hard 60 rubber composition, or any other suitable material, and which is formed to provide a central compartment 11 which extends into the body but not entirely therethrough. Externally of this central compartment 11 65 there are formed a series of longitudinally extending delivery compartments 12 which are open at opposite ends of the body. These delivery compartments are illustrated as being disposed concentrically to the central compartment 11 and these delivery compartments, as illustrated in Figure 4, are disposed relatively close to each other except at one point where a blank space 13 is left. I have illustrated the body as being 70 surrounded at its middle by a band 14 of metal or other suitable material, though I do not wish to be limited to this.

The inlet end or filling end of the receptacle is normally closed by means of a cap 80 15, which cap is preferably of metal and carries on its inner face a rubber pad 16. The opposite sides of the cap are formed with bayonet slots 17 and the body is formed with oppositely projecting pins 18 engaging 85 said bayonet slots. The angular ends of the bayonet slots are so formed or shaped that when the cap is inserted over the body and rotated in a direction to carry the pins 18 into the angular ends of the bayonet slots, 90 the cap will be drawn inward against the body and the rubber packing member 16 or pad compressed. The opposite end of the body is closed by a permanently attached, 95 rotatable cap 19. This cap is held in place upon the body by means of a centrally disposed, headed screw 20 or equivalent device whereby the cap may be rotated around the body. The cap is formed on its outer face with one single perforation 21 which is 100 adapted to register with any of the chambers 12 and the cap is held from accidental rotation by means of a spring projected pin 22 inserted in the side wall of the body and projecting out therefrom. This pin or detent is 105 beveled upon one face, as at 23, so that it acts as a pawl and engages any one of a series of perforations 24 formed in the side

wall of the cap. This detent pawl 23 acts to hold the cap in any rotated position to permit the rotation of the cap in one direction and one direction only.

5 In the use of this device, the chambers 12 are each to receive a match, the head of the match being preferably directed toward the cap 15. The central storage compartment 11 may be filled with matches for subsequent use. After the receptacle is filled, the cap 15 is put in place and locked by its bayonet slots and the pins 18. At this time the opening 21 is disposed over the blank space 13 and if a match is desired the cap 19 is 10 rotated one step so as to carry its aperture 21 over one of the chambers 12. Then the match, of course, is easily discharged into the hand. The detent 22 holds the cap from any further accidental rotation until the 15 next match is wanted, when the cap is again turned one step, and so on until all the matches have been discharged. Then the chambers 12 are refilled with matches and a new supply is disposed in the chamber 11. 20 The chamber 11 is designed to contain at least sufficient matches to refill the chambers 12.

I do not wish to be limited to the use of this device as a match safe or box or even as 30 a pocket match safe or box, as it also may be used for discharging cigarettes, in which case the chambers 12 will, of course have to be made large enough to receive each individual cigarette and the chamber 11 large 35 enough to receive a charge of cigarettes. I have illustrated in Figure 5 a receptacle designed to contain both cigarettes and matches, in which case the cigarettes will be contained within the relatively large chambers 25 and the matches within the relatively small chambers 26, these chambers 26 being disposed inward of the chamber 25 and there being two perforations 27 in the cap 19 so that the one step rotation of the cap will discharge both a cigarette and a match. Of course obviously the relative positions of the match chambers 26 and the cigarette chambers 25 may be changed so that a match and a cigarette will be alternately disposed. 40 Preferably the spaces 13 will be marked plainly so as to indicate at a glance that the matches in the chambers 12 have become exhausted and that the case needs refilling.

It will be understood that this device 55 might be made for a pocket or for the reception of matches for household use and that it might be mounted on a holder in the latter case so as to discharge the matches downward as the cap 19 is rotated.

60 While I have illustrated a device which is particularly adapted for the discharge of matches, I do not wish to be limited thereto, as it is obvious that it might be used for discharging other articles. Neither do 65 I wish to be limited to any particular con-

struction of the box. The middle portion 14 might also be formed with a match scratching surface 28.

I claim:

1. A holding and delivering receptacle of 70 the character described comprising a cylindrical body formed to provide a central compartment open at one end of the body and a plurality of longitudinally extending compartments arranged in a series concentric to the inner compartment and opening at opposite ends of the body and disposed between the central compartment and the periphery of the body whereby each article is held separate from and out of contact 80 with each other and with the articles in the central compartment, a cap detachably engaged with one end of the body and when engaged bearing against the wall between the central compartment and the other compartments, said cap closing the central compartment and the corresponding ends of the outer compartments, a cap rotatably mounted upon the opposite end of the body and having an aperture adapted to register with 90 any one of said outer compartments, and co-acting means on the body and cap permitting a one step rotation of the cap in one direction only with reference to the body. 95

2. A holding and delivering receptacle of the character described comprising a body having a plurality of longitudinally extending compartments opening upon opposite ends of the body, each compartment being 100 designed to hold one of the articles to be delivered and the compartments being arranged in a series concentric to the longitudinal axis of the body, a detachable cap at one end of the body bearing against the 105 body and closing the compartments at one end, a rotatable cap at the other end of the body having an opening adapted to register with any one of said compartments, a spring projected detent mounted upon the body and 110 having a beveled outer face, the rotatable cap being provided with perforations with which said detent is adapted to engage, the detent permitting a one step rotation of the cap in one direction. 115

3. A receptacle of the character described comprising a body having a central storage compartment open at one end of the body only, the body being formed with a plurality of longitudinally extending compartments arranged in a series concentric to the central compartment and opening upon opposite ends of the body, a detachable cap adapted to extend over that end of the body upon which the central compartment 120 opens, normally bearing against the outer wall of the central compartment, the opposite end of the body having a rotatable cap formed with a perforation adapted to register successively with the several outer com- 125

parts, there being coacting means on the body and cap permitting a one step rotation of the cap in one direction relative to the body.

- 5 4. A receptacle of the character described comprising a body having a central storage compartment open at one end of the body only, that portion of the body exterior to the central compartment being formed with 10 longitudinally extending compartments open at opposite ends of the body and arranged in a series concentric to the central compartment, a cap adapted to extend over that end of the body upon which the central compartment opens and normally bearing against the outer wall of said compartment and formed with bayonet slots in its side walls, the body having diametrically opposite pins with which said bayonet slots engage, the inner face of the cap having an elastic pad normally bearing against the end face of the body and the bayonet slots being formed to cause the cap being drawn against the body to compress said pad, the opposite 25 end of the body having a rotatable cap formed with a perforation adapted to register successively with the several outer compartments and there being coacting means on the body and cap permitting a one step 30 rotation of the body in one direction.
5. A receptacle of the character described comprising a cylindrical body formed with a central storage compartment extending from one end of the body nearly to the 35 other end thereof and opening upon one end of the body, the body being formed exteriorly of said central compartment with longitudinally extending compartments arranged in a series concentric to the axis of 40 the body and opening upon opposite end faces thereof, a detachable cap fitting over

and embracing that end of the body upon which the central compartment opens and normally bearing against that end of the body and bearing against the outer wall 45 of the central compartment, a rotatable cap fitting over the opposite end of the body and rotatably mounted thereon and formed with a perforation adapted to register successively with the several outer compartments, the body having a spring projected, bevel-faced detent carried in its side wall and the flange of said last named cap having a series of perforations with which said detent is adapted to engage, the detent 50 permitting a one step rotation of the cap in one direction relative to the body.

6. A receptacle of the character described comprising a body formed with two series of longitudinally extending compartments 60 opening upon opposite ends of the body, both series being disposed concentric to the central axis of the body, any opening of one series being in radial alignment with an opening of the other series, a detachable 65 cap closing one end of the body and extending over said series of compartments, and a rotatable cap mounted upon the other end of the body and extending over both series of compartments, said rotatable cap being 70 formed with two openings in radial alignment adapted to register simultaneously with any two compartments in radial alignment as the cap is rotated, the last named cap and the body being provided with co- 75 acting means for permitting a one step rotation of the body with relation to the body in one direction but preventing a reverse rotation of the cap.

In testimony whereof I hereunto affix my 80 signature.

ROBERT O. DUNNING.
